UNITED STATES PATENT OFFICE.

TAYLOR McDougall, of Pasadena, and Jesse Frank Smedley, of Los Angeles, California, assignors to Motorcycle Sweeper Company, of Los Angeles, California, a corporation of California.

STREET-SWEEPER.

1,369,118.

Specification of Letters Patent. Patented Feb. 22, 1921.

Application filed May 21, 1917, Serial No. 169,848. Renewed January 3, 1921. Serial No. 434,783.

To all whom it may concern:

Be it known that we, TAYLOR McDougall and JESSE FRANK SMEDLEY, both citizens of the United States, residing at Pasadena and 5 Los Angeles, respectively, in the county of Los Angeles and State of California, have invented a new and useful Street-Sweeper, of which the following is a specification.

The majority of motor vehicle street sweepers when constructed so as to sweep a 10 relatively great area are extremely costly, and in most instances are of a complicated and awkward construction. The principal objections to these machines are that they 15 are too costly, large, slow in operation and difficult to manage in city streets. Furthermore, these sweepers have not proved to sweep thoroughly, and raise dust in some instances. It is the primary object of this 20 invention to remove all of the foregoing objections to motor vehicle street sweepers by providing a street sweeping machine which is simple in construction, inexpensive in production and operation, extremely simple in 25 operation, capable of being propelled at a fair rate of speed during the sweeping action, and which does not raise dust.

An object of this invention is to provide 30 in a street sweeper a simple, effective and inexpensive means for removing all rubbish and dust swept up by a rotary street sweeping brush and causing it to be stored in such manner that little or no dust is raised or scattered during this operation.

35 A further object is to provide a brush and a suction member for removing the rubbish and dust swept up thereby which are so related to one another and to the vehicle upon which they are mounted that they may be easily moved into and out of sweeping position and are permitted to give in case an obstruction is encountered thereby.

An additional object is to provide for 40 the storing of rubbish and dust without scattering the dust and so that rubbish is stored in a sanitary, clean and desirable manner.

The accompanying drawings illustrate 45 the invention:

50 Figure 1 is a side elevation of the sweeper showing it broken away in part.

Fig. 2 is a fragmentary vertical sectional view showing the brush and other coöperat-

ing parts of the sweeping mechanism mounted on a vehicle.

55

Fig. 3 is a rear elevation of the sweeper.

Fig. 4 is a horizontal fragmentary sectional view with parts broken away to illustrate the exhaust fan and mechanism located beneath the dust collecting means in top 60 plan.

Fig. 5 is an enlarged fragmentary sectional detail of the brush supporting means showing a portion of the brush connected therewith.

65

Fig. 6 is a detail side elevation of the brush supporting means.

Fig. 7 is an enlarged fragmentary sectional view of the suction member.

Fig. 8 is a fragmentary sectional view 70 taken on lines 8—8 of Fig. 2.

Fig. 9 is a fragmentary rear elevation with the rear wall broken away showing the conical discharge member of the dust separator.

75

Referring to the drawings, 1 designates a motor vehicle which in this instance is a truck of standard construction, consisting of a rectangular frame or chassis 2, front and rear axles 3 and 4, wheels 5 and 6, on the respective axles, steering mechanism 7, motor 8 and other parts which need not be described.

A rotary, preferably cylindrical, street sweeping brush 9 is supported from the 85 frame 2 rearwardly of the wheels 6 by a brush supporting frame 10. The frame 10 comprises a horizontal shaft 11 rotatably journaled in bearings 12 depending from the frame 2. Mounted for swinging movement upon the bearings 12 are downwardly extending arms 13 which are extensible and formed in two sections 14 and 15. The sections 14 and 15 overlie one another and are provided with registering slots 16 and 90 17 which receive bolts 18 having nuts 19 thereon. By tightening the nuts 19 the sections 14 and 15 may be held in the desired relation. These arms may be taken up or let out dependent upon the degree of contact of the brush with the pavement desired. The brush 9 comprises a core 20 having a series of bristles 21 projecting from the periphery thereof. These bristles are arranged in a spiral formation and upon rotation of the brush direct the rubbish swept

95

100

105

up thereby from the right-hand end toward the left-hand end of the brush. Extending from the ends of the core 20 are trunnions 22 which are journaled in bearings 23 at 5 the lower ends of the arms 13. The trunnions extend through the arms 13 and outwardly therefrom. A sprocket 24 is secured by suitable means 25 to each of the trunnions 22 and chains 26 are mounted upon 10 the sprockets 24 and upon sprockets 27 which are fixed to the outer ends of the shaft 11.

Suitably mounted upon the frame 2 is a 15 motor 28 or other source of power having a drive shaft 29 which carries a sprocket 30. A chain 31 is mounted upon the sprocket 30 and upon a sprocket 32, the latter being fixed to a shaft 33 journaled in a bearing 34 of the frame 2 rearwardly of the motor 28. 20 Another sprocket 35 is journaled upon the shaft 33 and supports a chain 36 which is mounted upon a sprocket 37 fixed to the shaft 11. Through the foregoing chain or drive mechanism the brush 9 is operated. 25 Suitable means, not shown, may be provided to control the operation of the motor 28.

A semicylindrical dust hood 38 is fixed 30 to the bearings 23 and covers the brush 9 to prevent dust or rubbish from being thrown upwardly or scattered during the operation of the brush.

There is provided a means to raise or 35 lower the brush which comprises an operating lever 39 pivoted at 40 upon a bracket 41 secured to the frame 2. The lever carries a locking mechanism 42 which co-operates with a notched quadrant 43 and upon its lower end is pivoted as at 44 to one end of 40 a rod 45 which extends rearwardly to and is pivotally connected with a rocker arm 46, as at 47. The arm 46 is pivoted as at 48 to the frame 2 and at its upper end is pivoted at 49 to one end of a rod 50 which extends 45 downwardly and rearwardly and is pivotally connected at 51 with an arm 52. Pivoted to an arm 53 connected with one of the arms 13 is an arm 54 having pivotal connection 55 with the frame 2 at its upper 50 end and a pivotal connection 56 with the arm 52 so that when the rod 50 is pulled forwardly, the arm 52 will lift the arm 54 upwardly and the brush will be correspondingly lifted into out-of-the-way position.

55 Hook members 57 are secured to the frame 2 and are adapted to engage with the bearings 23 to hold the brush in up position.

There is provided a suction means for 60 collecting rubbish and dust swept up by the brush and depositing it into a receptacle which will be later more fully described. This means comprises a hollow suction member 58 which is supported in a downwardly and rearwardly inclined position in front 65 of the brush 9 and has downwardly con-

vergent walls 59 which provide a relatively narrow intake opening 60 at the lower end of the member 58. The member 58 is approximately equal in width to the length of the brush and its open lower end 60 is located in close proximity to and above the lower side of the brush. Mounted upon the member 58 on opposite sides of its lower end are angle bars 61 and 62, and secured to the angle bar 61 is a deflector plate 63 70 which extends toward the brush in an approximately horizontal plane and has its upper edge slightly spaced from the bristles of the brush. This plate extends for approximately the entire length of the brush 75 and serves to prevent rubbish from being thrown upwardly. An extension plate 64 is forwardly slidably adjustably mounted by suitable means 65 upon the plate 63 and may be extended when the brush becomes worn 80 so that it will prevent rubbish from being thrown upwardly between the baffle plate 85 and brush.

Hingedly secured to the angle bar 62 as 90 at 66 is a closure plate 67 which is adapted to be moved toward the open end 60 to restrict the opening into the member 58 and produce a greater suction. This plate 67 receives the rubbish swept up by the brush, prevents it from being thrown under and in 95 front of the member 58 and extends for a distance equal to approximately the entire length of the brush. At its ends the plate 67 has pivotal connections 68 with links 69 which have pin and slot connection 70 with 100 the arms 13 of the brush supporting frame 10. It will thus be seen that when the frame 10 and brush are lifted up, the links 69 will lift the plate 67 upwardly and the opening 60 will be restricted causing any rubbish 105 upon the pavement adjacent to the suction member or upon the plate 67 to be readily sucked into the member 58. This prevents the leaving of a pile or rift of rubbish at the point where the brush ceases operation. 110 If the frame 10 and brush are lifted a greater distance than sufficient to close the plates 67 the links 69 will then operate to raise the entire suction member 58. This provides for raising the suction member 115 temporarily to avoid contact with an obstacle during the street sweeping operation or to raise the suction member into an out-of-the-way position while traveling to and from the street to be swept.

120 There is provided a supporting means for the suction member 58 which comprises an angle bar 71 extending along and engaging the under side of the member 58 at a point approximately centrally of its upper and lower ends. This bar 71 is supported by angular hangers 72 which are secured to the frame 2 of the motor vehicle. When the member 58 is in down position it rests upon and is supported by the bar 71.

At its upper end the member 58 is centrally provided with a cylindrical outlet nipple or spout 73 which is connected by a flexible coupling member 74 with the lower 5 end of a suction pipe 75. The pipe 75 is connected with the chamber 76 of a rotary exhaust fan 77, the latter being mounted upon a suitable supporting structure 78 fixed to the frame 2. The flexible coupling 10 74 permits the upward and downward movement of the member 58 in correspondence with the movement of the brush 9.

The motor shaft 29 carries a sprocket 82 upon which is mounted a chain 83 for driving the exhaust fan 77. The shaft 84 of the exhaust fan carries a sprocket 85 around which the chain 83 is rove. Mounted upon the shaft 84 is a sprocket 86 upon which is mounted a chain 87. This chain 87 extends 20 downwardly and around a sprocket 88 which is journaled upon the frame 2 upon a shaft 89. A crank 90 is fixed to the shaft 89 and provides a means for cranking or starting the motor 28. The starting motion being 25 transmitted from the sprocket 88 through the chain 87, sprocket 86, shaft 84, sprocket 85, chain 82 to motor shaft 29.

A preferably rectangular housing 91 is mounted upon the frame 2 of the vehicle 30 and incases the exhaust fan 77, pipe 75 and coöperating mechanism which extends above the frame 2. This housing 91 has its forward end closed by a wall 92 to which are joined side walls 93. The rear end of the 35 housing 91 is open on the lower side and a door 94 which is hinged as at 95 to the outer end wall 96 of the housing closes the open lower side of said outer end and is held in closed position by latch mechanism 96' 40 of any suitable character. The housing 91 is divided interiorly by a partition wall 97 which extends downwardly and rearwardly from the upper front end of the housing to the lower rear end thereof above the exhaust 45 fan 77 and coöperating mechanism. The lower end of the partition wall 97 terminates at a point adjacent to the lower edge of the door 94 and this wall provides a rubbish and dust chamber in the upper part of the 50 housing. A blower or exhaust pipe 98 extends upwardly from the exhaust fan 77 through the wall 97 and upper wall 99 of the housing above said upper wall, and at its upper end is connected by an elbow 100 55 with a cyclone intake 101 extending laterally from one side of a dust cyclone member 102. This member 102 comprises a cylindrical body portion 103 which at its lower side communicates with a frusto-conical discharge member 104. The frusto-conical member 104 is carried by the upper wall 99 60 of the housing and has its discharge opening 105 located directly above the wall 97. The body portion 103 of the cyclone is formed 65 with a central cylindrical outlet spout 106,

the upper end of which communicates with the atmosphere, whereas the lower end communicates with the upper end of the frusto-conical member 104. A downwardly and outwardly inclined annular baffle member 70 107 is secured to the outer side of the member 106 adjacent to the lower end thereof so as to direct heavy particles of rubbish blown into the cyclone away from the lower end of the member 106 toward the outer 75 downwardly converging walls 104 whereby the heavy particles of rubbish will readily discharge from the opening 105 onto the wall 97. To prevent back pressure with the escape of an appreciable amount of rubbish or dust from the cyclone, there is provided 80 a baffle plate 108 which is located in spaced relation to the lower end of the member 106 at a point directly over the opening 105 of the member 104. Hangers 109 secured to the lower end of the member 106 support the plate 108 in horizontal position and in spaced relation to the member 104. There is provided an auxiliary air outlet 85 110 in the upper wall 99 of the housing and 90 communicating with the dust and rubbish chamber therein. This opening 110 has an upwardly extended nipple 111 communicating therewith, the top of which is covered 95 with suitable screen 112 to prevent the escape of dust.

There is provided a sprinkling means to prevent the flying of dust from the discharge of the cyclone and this means comprises a sprinkler nozzle 113 located within the discharge or outlet of the cyclone. The nozzle 113 is secured upon the lower end of a pipe 114 which is connected with a horizontal pipe 115 extending across the top of the cyclone to a pipe 116 which is connected with 100 a water supply tank 117 mounted upon the upper wall 99 of the housing. An air pump 118 is provided for creating a pressure in the tank 117 so that a spray will be forced 105 through the nozzle 113. The tank 117 is provided with a suitable filling opening 119 closed by a cap 120. A gage 121 is mounted upon the tank indicating the air pressure therein and the spray may be controlled by a valve 122 connected with the tank 117. 115

To sweep, the brush is lowered into the position shown in Fig. 1 of the drawings by releasing the lever 39 and pushing it forwardly. When the brush is lowered or prior to the lowering of the brush, the motor 28 is started by means of the crank 90, gear 88, chain 87, sprocket 86, chain 83, to motor shaft 29 and power is transmitted from the engine 28 through shaft 29, chain 31, sprocket 32, shaft 33, sprocket 34, 120 chain 36, sprocket 37, shaft 11, sprocket 27, chain 26 and sprocket 24. Through this drive arrangement the brush is rotated clockwise and tends to throw dust and rubbish forwardly and upwardly into the open 125 130

1
end 60 of the suction member 58, said suction member being lowered into position when the brush and brush frame are lowered. Since the plate 63 and extension plate 64 are located in close proximity to the bristles of the brush above the lower side thereof, rubbish and dust are prevented from being thrown upwardly. In case the brush wears down the extension plate 64 may be moved so as to lie close to the bristles of the brush. The closure plate 67 prevents rubbish and dust from being thrown forwardly under the open end 60 of the member 58 and serves to direct rubbish and dust upwardly into the suction member. The links 69 which connect the plate 67 with the brush frame 10, in having pin and slot connections with said brush frame allow for a yielding movement of the suction member in case an obstruction is encountered and thereby prevent injury to the suction member. The exhaust fan 77 is operated from the motor shaft 29 by the chain 83 mounted upon the 25 sprocket 85 of the fan shaft 84 and the suction produced by the fan causes all of the rubbish and dust thrown into and adjacent the lower open end 60 of the member 58 to be drawn upwardly through said member 58, pipe 75 into the fan chamber 76, from thence the rubbish and dust are blown through the exhaust pipe 98 into the cyclone 102. The rubbish and dust which is blown into the cyclone 102 from one side 35 thereof is caused to swirl or rotate rapidly within the body portion 103 of the cyclone and the heavier particles of rubbish will drop downwardly upon the frusto-conical lower portion 104 of the cyclone 40 and discharge through the opening 105 onto the partition wall 97 which forms a rubbish and dust receptacle within the upper portion of the housing 91. The cylindrical discharge member 106 located with- 45 in the body portion 103 has its intake end at the lower side of the body portion 103 and the baffle member 107 in being inclined downwardly and outwardly toward the outer walls of the body portion 103 pre- 50 vents rubbish and dust from being conducted too near the lower or intake end of said member 106 and directs said rubbish and dust away from said lower open end so that it will fall into the member 104 and 55 discharge through the opening 105 thereof. The air blown into the cyclone will discharge through the member 106 and by means of the sprinkling arrangement which includes the nozzle 113 located centrally 60 within the member 106 water is introduced into the cyclone and prevents dust from being blown out through the member 106 with the escaping air. The tank 117 con- 65 tains water under air pressure, the air being forced into the tank by means of the

pump 118. The water will be sprayed into the cyclone when the valve 122 at the top of the tank is open. The baffle plate 108 relieves back pressure and prevents rubbish and dust from being forced upwardly 70 and discharged through the member 106 with the air. For this reason the baffle plate 108 is located above the discharge opening 105 of the member 104 and beneath the intake opening of the member 106. 75

As the motor vehicle is propelled the brush rotates so as to throw the rubbish and dust in the direction of the movement of the vehicle into the suction member which is located in front of the brush and 80 owing to this arrangement which is one of the most essential features of the invention, the vehicle may be propelled rapidly and a thorough and reliable sweeping or street cleaning action provided for without the 85 scattering of dust. By grasping the lever 39 and pulling it rearwardly, an upward pull is communicated to the rod 49, rocker arm 46, rod 50, link 52 and arm 54 connected with the brush hood 38. When the brush is lifted upwardly the links 81 connected with the plate 67 lift the suction member 50 upwardly also and in lifting it move the plate 67 so as to restrict the opening 60 in the lower end of the member 58. 95 When this is done the suction at the lower end of the member 58 is increased causing all particles of the dust and rubbish adjacent to said lower end or which may be lodged in the suction member to be readily 100 sucked into the member and discharged into the cyclone. The door 94 may be opened to remove the rubbish contained within the upper portion of the housing 91.

It will be noted that the suction member 105 58 and brush are supported by such construction and in such manner that should an obstruction be encountered thereby no damage will be done owing to the fact that both the member 58 and brush are permitted to swing or give upwardly. The brush 9 is of a spiral form, as previously described, the bristles being so arranged as to work the rubbish from the right toward the left side of the brush. This is desirable, as in sweeping a street the machine is driven along the right-hand side thereof and since the streets are usually inclined downwardly on the sides thereof the right side of the brush is lowermost and in working the rubbish toward the left side thereof provides for a thorough, expeditious and effective sweeping action. 115

With reference to the description and accompanying drawings, it will be seen that 125 we have provided a street sweeping machine which may be readily attached to a modern vehicle, preferably a truck, without requiring any material change in the construction of the truck and so as to pro- 130

vide a motor vehicle street sweeper capable of being operated at a fair rate of speed, say twelve miles an hour, and of sweeping a wide expanse of a street thoroughly, 5 quickly, inexpensively and without causing dust to be scattered.

We claim:

1. In a street sweeper, a frame, a brush supported by the frame, a suction member having its lower open end located adjacent to the brush, means to create a suction in the suction member, means to raise and lower the brush, and means to gradually restrict and widen the opening in the lower 10 end of the suction member as the brush is raised and lowered respectively.
2. In a street sweeper, a brush supporting means movable up and down, a brush carried by said means, means to rotate the brush, a suction member having an intake opening located adjacent to the brush to receive rubbish swept up thereby, means to create a suction in said suction member, means to raise and lower the brush, and means to gradually restrict the intake 15 coincident with the raising of the brush.
3. In a street sweeper, a frame, a sweeping brush, a suction member having an intake opening located adjacent to the brush, means to create a suction in the suction member, means to restrict the intake opening in the suction member, means to raise and lower the brush, and means connecting the means to restrict the intake opening to the means for raising and lowering the brush and adapted to restrict and open the 20 intake opening as the brush is raised and lowered respectively and to raise the suction member by a further raising of the brush after the intake opening has been closed.
4. In a street sweeper, a brush supporting means movable up and down, a rotary brush carried by said means, means to rotate the brush, a suction member having an intake opening located adjacent to the brush, means to create a suction in said member, a plate movable toward and away from said intake opening, means to raise and lower the brush 25 and link members connecting the said plate with the said brush raising means.
5. In a street sweeper, a brush supporting means, a brush carried by said means, means to rotate the brush, a suction member having an intake opening located adjacent to the brush to receive rubbish swept up thereby, means to create a suction in said member, a plate hinged to said suction member along one edge of said intake opening and movable toward and away from the other edge of said opening, means to raise and lower the brush and means connecting the plate to the brush supporting means.
6. In a street sweeper, a brush supporting means, a brush carried by said means, means 30 to rotate the brush, a suction member having an intake opening located adjacent to the brush to receive rubbish swept up thereby, means to create a suction in said member, a plate hinged to said suction member along one edge of said intake opening and movable toward and away from the other edge of said opening, means to raise and lower the brush operating to move the plate toward the opening when the brush 35 is raised and away from the opening when the brush is lowered, including links pivoted to the plate and brush supporting means.
7. In a street sweeper, a brush supporting means, a brush, means to rotate the brush, a suction member having an intake opening, means to create a suction in said member, means to restrict the intake opening, means to raise and lower the brush supporting means, and means to raise the suction member after the intake opening has been closed by further raising the brush supporting 40 means.
8. In a street sweeper, a brush supporting means, a brush carried by said means, means to rotate the brush, a suction member having an intake opening located near said brush, means to create a suction in said member, means between the intake opening and brush to prevent rubbish from being thrown upwardly above the intake opening, and means to restrict the intake opening to increase the suction force at said opening.
9. In a street sweeper, a brush supporting means, a brush carried by said means, means to rotate the brush, a suction member having an intake opening located near said brush, means to create a suction in said member, means between the intake opening and brush to prevent rubbish from being thrown upwardly above the intake opening, said intake opening being located in front of the brush, means to raise and lower the brush supporting means, and means to restrict the intake opening to increase the suction force at the opening.
10. A street sweeper comprising a brush supporting frame, a brush carried by the frame, means to rotate the brush, a suction member to receive rubbish swept up by the brush, having an intake opening located adjacent to the brush, a plate carried by the suction member and extending from the upper edge of the opening toward the brush in approximate contact with the brush, and an extension plate adjustably mounted on the first plate.
11. A street sweeper comprising a brush supporting frame, a brush carried by the frame, means to rotate the brush, a suction member to receive rubbish swept up by the brush, having an intake opening located adjacent to the brush, a plate carried by the suction member and extending from the upper edge of the opening toward the brush

- in approximate contact with the brush, an extension plate adjustably mounted on the first plate, a plate hinged to the suction member at the lower side of the intake opening and extending downwardly therefrom normally, and means to move the plate toward and away from the opening.
12. In a street sweeper, a vehicle frame, brush supporting arms pivoted to the frame, a brush carried by the arms, means to rotate the brush, means to raise and lower the brush and supporting arms, a suction pipe on the vehicle frame, means to create a suction in said pipe, a suction member, a flexible coupling member secured to the pipe and suction member, said suction member having an intake opening located in front of and near the brush to receive rubbish swept up by the brush, a plate hinged to said suction member along the lower side of the intake opening and normally extending downwardly therefrom, and a connection between the plate and brush supporting arms, said intake opening extending for the length of the brush.
13. In a street sweeper, a vehicle frame, brush supporting arms pivoted to the frame, a brush carried by the arms, means to rotate the brush, means to raise and lower the brush and supporting arms, a suction pipe on the vehicle frame, means to create a suction in said pipe, a suction member, a flexible coupling member secured to the pipe and suction member, said suction member having an intake opening located in front of and near the brush to receive rubbish swept up by the brush, a plate hinged to said suction member along the lower side of the intake opening and normally extending downwardly therefrom, a connection between the plate and brush supporting arms, said intake opening extending for the length of the brush, and a plate secured to the suction

member along the upper edge of the intake opening and extending in close relation to 45 the brush.

14. In a street sweeper, a vehicle frame, a brush, a brush supporting means pivoted to the frame and adapted to allow the brush to rest on a street surface, a suction member having an intake opening adjacent to the brush, means to create a suction in the suction member, means to restrict the intake opening of the suction member, and means connecting the last named means with the brush supporting means and adapted to restrict and widen the intake opening as the brush moves up and down respectively along the street surface.

15. In a street sweeper, a vehicle frame, a brush, a brush supporting means pivoted to the frame and adapted to allow the brush to rest on a street surface, a suction member having an intake opening adjacent to the brush, means to create a suction in the suction member, means to restrict the intake opening of the suction member, means to raise and lower the brush by swinging the brush supporting means on its pivot, and a link member connecting the means to restrict the intake opening of the suction member to the brush supporting means and adapted to restrict and widen the intake opening and to raise and lower the suction member as the brush is raised and lowered respectively, either by the means to raise and lower the brush or by the brush moving up and down along the street surface.

In testimony whereof, we have hereunto set our hands at Los Angeles, California, 80 this 17th day of April, 1917.

TAYLOR McDougall.
